LETTERING MACHINE

Leonard McDonald, El Campo, Tex.

Application March 9, 1931, Serial No. 521,273

11 Claims. (Cl. 33—25)

This invention relates to lettering machines of the type carrying an interchangeable plate of master letters or other characters and a pantograph for copying the characters of the master copy on a drawing surface over which the machine moves. In practice the master copy will consist of grooved characters, the grooves serving to guide the tracer, but the machine is useful and operative with characters not grooved. This machine is designed to operate independent of guide bars, or straight-edges such as are used in my Patent No. 1,784,152, granted December 9, 1930 and application Ser. No. 490,880, filed October 24, 1930, for maintaining parallelism of its movement. Parallelism of its movement is obtained by means of an axle having a fixed wheel on each end adapted to roll on a drawing surface, the wheels having friction material on their peripheries, such as rubber having sharp granular material incorporated with it, to prevent accidental displacement. It may be lined up for use by adjusting it so as to make marks on the upper and on the lower side of the machine coincide with a line drawn as required on the drawing surface. It is also adapted to be connected with a protractor of the type guided for parallel movement by parallel jointed rods attached to the protractor and to a drawing board. The rolling wheels of the machine prevent sidewise displacement and the protractor prevents angular displacement. It is also adapted to be connected with a straight-edge to prevent angular displacement. The device includes letter spacing mechanism adapted for this type of machine, and a new mechanism for shifting each master character into position for being copied in line. The device further has a new arrangement of the support and pantograph, whereby the pantograph draws through a circular opening in the support, which contributes to compactness of the machine, and it includes means for mounting the pantograph so that the rear end of it will have nearly as much up and down movement as the front of it, thereby causing the drawing member, even when it is at its extreme rear position, to make and break contact with the drawing surface without great up and down movement of the front end of the pantograph, and other improvements hereinafter described.

These mechanisms are illustrated by the accompanying drawings, of which Fig. 1 is a plan view. Fig. 2 is a sectional side elevation on the line 2—2 of Fig. 1. Fig. 3 is an end view of the rear part of the machine on the line 3—3 of Fig. 1. Fig. 4 is a broken side view of the same, showing the mechanism for operating the pawl. Fig. 5 is a sectional view on the line 5—5 of Fig. 1, showing the spacing mechanism. Figs. 6 and 7 show the top and end view of the bar for attaching the machine to the protractor. Figs. 8 and 9 show top and side views of one of the bars for connecting it with a straight-edge. Fig. 10 shows a modification of the mounting of the pantograph. Fig. 11 shows a pawl adapted to be operated direct by the thumb. Fig. 12 shows the machine connected with a protractor controlled by parallel jointed rods. Fig. 13 shows it connected with a straight-edge.

The supporting plate 1 has bearings 2 for axle 3, which has a wheel 4 fixed on each end for rolling movement of the machine over a drawing surface. The machine is used independent of guide bars, or straight-edges for maintaining its angular position and thereby preserving parallelism. But where a protractor of the type having parallel jointed rods attached to a drawing board and to the protractor for maintaining it at a fixed angle is being used, the machine may be attached to it by a bar 5 attached to the under side of the machine, having a dove-tail part adapted to slip into the rule-holding chuck 6 of the protractor (see Figs. 6, 7, and 12) for preventing angular displacement of the machine. The term "protractor" as herein used includes the supporting plate to which the parallel jointed rods are attached and all parts of the protractor mounted on the plate or where a straight-edge of the type held for parallelism of its movement by the usual pulleys and cord devices attached to the drawing board, or by any other suitable means for the same purpose, is being used, the machine may be connected with it by two bars 7 (see Figs. 8, 9, and 13) having a block 8, and screw 9 slidable in slot 10 for adjusting the block to different size straight-edges. Fins 11 prevent disconnection. With this arrangement means for preventing endwise movement of the straight-edge is unnecessary, as this will be prevented by the frictional contact of wheels 4 with the drawing surface.

Supporting plate 1 has a circular opening 12. A bearing 13 is a drive fit in the opening, and with the balls 14 forms the bearings for annular member 15. An annular plate 16 has spaced master characters on it, some of the characters having the elements of several letters or figures superposed for convenience of tracing, and is removably mounted on member 15 and is held rotatable therewith by pin 17, and has a notch 18 on its periphery for each character. A pawl 19 pivotally mounted on supporting plate 1 is held in en-

- gagement with any one of notches 18 by spring 20 attached to supporting plate 1 and to the pawl, for locating and holding each character in position for being copied in line by the pantograph.
- 5 The means for revolving plate 15 comprises a shaft 21 having spiral grooves, mounted on supporting plate 1, its lower end being supported by ball bearings formed by supporting plate 1 and annular bearing 22 held in place by screws 23, the shaft having a conical end and a conical headed screw 24 for bearings. The upper end of the shaft has a bearing on support 25, which is held in place on supporting plate 1 by two screws 26. A nut 27 has internal threads engaging the grooves on shaft 21 and is prevented from revolving by slot 28 engaging support 25. A handle 29 is pivoted to two arms 30 on nut 27 for slight angular movement limited by bar 31 attached to handle 29 coming into contact with 10 nut 27. A spring 32 connected to the lower part of support 25 and to the under side of the handle normally holds the nut and handle at their highest position on shaft 21, and is connected to the handle some distance to the rear of its pivotal bearings to normally hold the handle in the forward position of its pivotal swing. A disk 33 is fixed to the lower end of shaft 21 and has frictional contact with annular member 15, and may have special friction material on its periphery, where- 15 by up and down movement of handle 29 revolves member 15, for bringing each character of the master copy into position for being copied in line. Disk driving member 33 need not be a disk in all equivalent mechanisms.
- 15 Means for operating pawl 19 from the handle, comprises, an inclined rod 34 having bearings at one end on support 35 on supporting plate 1, and an integral arm 36 connected by link 37 to pawl 19. The opposite end of rod 34 has bearings on 20 nut 27, and an integral arm 38 connected to hook link 39, the upper or hooked end of which extends through U-shaped rod 39a fixed to the side of the handle. The hook is held out of engagement with the U-shaped rod by spring 39b, but may be pressed into engagement with it by the thumb, whereby rearward movement of the handle on its pivotal bearings will disengage pawl 19 from notches 18. A short slot 40 in link 37 allows the handle to resume its forward position while the 25 point of the pawl 19 is sliding on the periphery of plate 16 between notches 18. The pantograph comprises bars *a*, *b*, *c*, and *d* pivoted together end to end and a bar *f* has a slot in each end to receive bars *b* and *c*, and has a slot *g* in which two 30 plates *h* and *i* having splines fitting in the slots are slidably mounted, *h* having a plain hole and *i* having a threaded hole which receive threaded tubular member *j*. The tubular member has a shoulder *k* contacting with plate *h*. Drawing member *e* is slidably mounted in the tubular member. A spring *l* encircles the under side of collar *m* on the tubular member, and the upper side of collar *n* on the drawing member, and normally holds the drawing member at its lowest position 35 in the tubular member.
- 35 Means for adjusting the pantograph for copying in various sizes, comprises an extension *o* on bar *a* to which a spring *p* is attached. A cord *q* has one of its ends attached to spring *p* and its other end attached to extension *r* on bar *d*, and extends over the outer side of single-grooved wheel *s* pivoted on the under side of one end of slotted bar *f* and over the outer side of a double-grooved wheel *s2* pivoted on the under side of 40 the opposite end of bar *f*. One end of cord *t* is attached to spring *u* which is attached to extension *v* of bar *a*, and is wound once around double-grooved wheel *s2* from the inner side of the wheel and its other end is attached to the under side of the near end of bar *d*. Bar *c* has a slot *w* extending the length of the travel of bar *f*. A pin *x* in bar *f* is a close fit in slot *w* to prevent endwise movement of bar *f*. An opening *y* in bar *f* permits a view of the graduation marks on bar *c*. Cord *q* is attached by a screw and clip *z* to one edge of plate *i*, whereby the drawing member may be adjusted for copying in different sizes simply by sliding tubular member *j* in slot *g*, which moves bar *f* until the opening *y* in bar *f* coincides with the required graduation mark. 45 My application Ser. No. 490,880 contains a description of this pantograph.
- 45 The pantograph is mounted as follows:
- 50 An arm 41 has conical bearings 42 on bearing block 43 secured to supporting plate 1 by screws 44, for slight up and down movement of the arm in a plane at right angles to the face of supporting plate 1, and is held slightly elevated by spring 45 connected with the arm and supporting plate 1. The spring is offset to obtain a sort of toggle 55 action, whereby the resistance of the arm will be the same in all of its positions of elevation. On the free end of the arm is a stud pivot 46 on which the pantograph is mounted to swing in a plane horizontal to the face of plate 1 when the pantograph is in its working position. Inner sleeve 48 on pivot 46 is integral with arm *a* of the pantograph, and outer sleeve 49 is integral with arm *b* of the pantograph, held on the pivot by nut 50. The pantograph has a tracer 51 slidably 60 mounted in sleeve 52, which sleeve is integral with arm *d* of the pantograph. The tracer is normally held at its lowest position in the sleeve by a spring 53 encircling sleeve 52, and tracer 51 above collar 54 fixed to the tracer, whereby downward movement of the pantograph by operating handle 55 pivoted to collar 56 which collar is slidably and rotatably mounted on the tracer, will cause the tracer to contact with the master copy before a further downward movement of the 65 pantograph will bring the drawing member *e* into contact with the drawing surface.
- 65 The object of mounting the pantograph on arm 41 is, that by so doing the rear end of the pantograph will be depressed nearly as much as the front end, thereby bringing the drawing member into contact with the drawing surface with only moderate downward movement of the front end, even when the drawing member is adjusted to its extreme rear position to draw the smallest size letters possible, whereas if the pantograph were pivoted direct to the plate 1 great up and down movement of the front end of the pantograph would produce only slight up and down movement of the rear or pivoted end. The arm 41 will preferably be Y-shaped when used in a lettering machine not having a disk 33 in the way, with its two conical bearings sufficiently far apart to prevent twisting flexibility of the arm. 70 Or if an arm not forked is used its single bearing must be sufficiently long to prevent twisting flexibility. The arm may be mounted to one side of the rear end of the pantograph, in which case the up and down movement of the rear end will be about equal to that of the front end. Or it may be mounted straight in the rear of the pantograph, in which case the degree of the up and down movement of the rear end relative to that of the forward end will depend on the length of 75

the arm and the swinging position of the pantograph with respect to the arm.

Means for spacing the copied letters, or characters, comprises, a disk 57 fixed to shaft 3, a graduated arc 58 secured to supporting plate 1, an arm 59 having bearings on shaft 3 for angular movement, having a slot 60 in its outer end to receive the arc, and a slot 61 extending a greater part of its length, and a thumb screw 62 for clamping it to arc 58 at the mark indicating the required distance. An arm 63 has bearings on shaft 3 between disk 57 and arm 59. A pawl 64 is pivoted to the outer end of arm 63, its point projecting inwardly and contacting with the periphery of disk 57 the radial length of the pawl being a little greater than the distance between its pivotal center and the periphery of the disk whereby toggle-clutch action is obtained. With forward movement of the carriage the disk carries the arm with it, which movement is limited by the arm contacting with pin 65 on supporting plate 1. An over projecting lug 66 on arm 63 limits the upward movement of the point of the pawl. A spring 67 bowed at its rear end and having its rear rounded point fitting loosely in a hole 67a in the hub of arm 63, is connected to the forward part of pawl 64 center over its pivotal bearings when the pawl is in its neutral position, whereby when the point of the pawl is raised the spring will hold it out of contact with the periphery of disk 57, and when depressed the spring will hold it in contact with the periphery of disk 57. A cupped spring washer on the pivot of the pawl, or a tight bearing would hold the pawl in its elevated position without spring 67. A coiled spring 68 (see Fig. 5) is attached to the hub of the arm 63 and to supporting plate 1, whereby, when the pawl is lifted arm 63 is thrown back to arm 59 which has an inclined surface 69 which turns the point of pawl 64 into contact with the periphery of disk 57 again. A pawl 70 is pivoted to an extension 71 of arm 59, its point projecting inwardly and forward of its pivotal bearings, and is held in contact with the periphery of disk 57 by spring 72. Pawl 70 prevents rearward movement of the machine, and its upwardly extending part may be depressed by a finger when it is desired to run the machine backward, and the upwardly extending part of pawl 64 may be depressed when it is desired to run the machine forward without spacing. There are numerous obvious means for lifting pawl 64 out of contact with the disk. The most convenient but not the simplest means for this purpose would be connected to the handle to be operated by movement of the handle. For this method, an inclined rod 73 has bearings at one end on support 74 on supporting plate 1, and an integral crank shaped arm 75, the end of which extends under the pawl 64. The opposite end of rod 73 has bearings on nut 77, and an arm 76 connected by link 77 to the upper forward part of handle 29, whereby rearward movement of the handle on its pivotal bearings lifts the point of the pawl.

65 A downwardly extending flange 78 on the upper and on the lower edge of the machine, has a mark 79 by which the machine may be adjusted to a line drawn on the drawing surface.

Fig. 10 shows a modification wherein the supporting arm A corresponding to 41, has its conical bearings B sufficiently far apart to clear disk 33, permitting it to be mounted on studs C on supporting plate 1 straight in the rear of the pantograph instead of to one side, and it is held up by spring D. And a simpler pawl E, may be used

with either type. See also Fig. 11. This pawl is mounted on plate 1 in the same manner as pawl 19, except that it has a long integral hub bearing F on stud pivot G. It has no connection with the handle, but has an upwardly extending part H which may be engaged by the thumb.

I claim:

1. In a lettering machine, a support, a circular plate rotatably mounted on said support, spaced master characters on said circular plate, a pantograph mounted on said support for copying said characters on a drawing surface over which said support may be arranged to move, a shaft vertically mounted on said support having spiral grooves, a nut having internal threads 10 engaging said grooves, a handle connected with said nut, means preventing rotation of said nut, so that longitudinal movement of the nut revolves said shaft, a driving member attached to the lower end of said shaft having a driving connection with said circular plate for revolving the required master character into position for being copied in line, there being a notch on the periphery of said plate for each character, a pawl pivoted to said support, and a spring holding it in 20 engagement with any one of said notches.

2. A carriage, comprising a supporting plate, an axle journaled on said supporting plate, and a wheel fixed on each end of said axle for parallel rolling movement of said carriage on a drawing surface, there being a circular opening in said supporting plate, an annular member, having bearings around said circular opening, a shaft vertically mounted on said supporting plate, having spiral grooves, a nut having internal threads 30 engaging said grooves, means for preventing rotation of said nut, a handle connected with said nut, whereby up and down movement of the handle will revolve said shaft, a spring under said handle tending to force it to its highest position 40 on said shaft, a disk fixed to the lower end of said shaft having frictional contact with said annular member for revolving it, an annular plate mounted on said annular member, rotatable therewith, having master characters thereon, and 45 a notch on its periphery for each character, a pawl pivoted to said supporting plate, a spring for holding said pawl in engagement with any one of said notches, for locating the characters in 50 position for being copied in line, a pantograph carried by said supporting plate mounted to extend over said circular opening, having a tracer for tracing said characters, and a drawing member for copying said characters through said circular opening on a drawing surface. 55

3. In mechanism as in claim 2, an inclined rod having at one end a fixed bearing on said supporting plate and an arm and a link connected to the end of the arm and to said pawl, its opposite end having a bearing on said nut and an arm and a hook link connected to the end of the arm, adapted to be pressed into engagement with said handle, pivotal bearings for said handle, and means connecting said pivotal bearings with said nut, for slight angular movement of said handle 60 for operating said pawl.

4. With mechanism as in claim 2, spacing mechanism, comprising, a disk fixed on said axle, a graduated arc adjacent said disk, secured to said 70 supporting plate, an arm having bearings on said axle for angular movement, split a greater part of its length, having a slot in its outer end for receiving said arc, and a screw for clamping it to said arc at the mark indicating the required space- 75;

ing distance, an arm having bearings on said axle adjacent the first mentioned arm, a pawl pivoted to its outer end, the point of the pawl projecting inwardly and contacting with the periphery of the disk with toggle-clutch action, whereby the arm is revolved by the disk by forward movement of the carriage, a pin projecting up from said supporting plate limiting the movement of the arm, an inclined rod having at one end bearings on said nut, and an arm and a link connected to the end of the arm and to said handle, pivotal bearings for said handle, and means connecting said pivotal bearings with said nut, the opposite end of the rod having fixed bearings on said supporting plate, and an arm projecting under said pawl, whereby angular movement of said handle will lift said pawl out of contact with said disk, a spring having one end fixed to said last mentioned arm and its other end fixed to said supporting plate, whereby the arm, when released by the operation of said handle, is thrown back to the first mentioned arm, which has an inclined surface that turns the point of the pawl into contact with the periphery of the disk, a pawl attached to the first mentioned arm, its point projecting inwardly of its pivotal bearings, and a spring holding it in contact with the periphery of the disk, to prevent rearward movement of the carriage.

30 5. A lettering machine, comprising, a carriage consisting of a support, an axle journaled on said support, and a wheel fixed on each end of said axle for parallel rolling movement of said carriage, a master copy mounted on said support, and a pantograph mounted on said support for copying the characters of the master copy on a drawing surface over which said lettering machine moves, and means for spacing the copied characters, comprising a disk fixed on said axle, a graduated arc adjacent said disk secured to said support, an arm having bearings on said axle for angular movement, split a greater part of its length, having a slot in its outer end to receive said arc, and a screw for clamping it to the arc at the mark indicating the required spacing distance, an arm having bearings on said axle adjacent the first mentioned arm, a pawl pivoted to the outer end of it, the point of the pawl projecting inward of its pivotal bearings and contacting with the periphery of the disk, whereby the arm is revolved by the disk by forward movement of the carriage, a pin projecting up from said support limiting the movement of the arm, means for lifting said pawl out of contact with said disk, a spring having one end attached to the last mentioned arm and its other end attached to said support, whereby the arm, when the pawl is released, is thrown back to the first mentioned arm, which has an inclined surface which turns the point of the pawl into contact with the periphery of the disk, and a pawl attached to the first mentioned arm, its point projecting inward of its pivotal bearings, and a spring holding it in contact with the periphery of said disk.

6. In mechanism as in claim 2, a spring connected with said pantograph and said tracer normally holding the tracer at its lowest position on said pantograph, an arm having bearings on said supporting plate for angular movement of the arm in a plane at right angles to the face of said plate, a spring connected with said plate and said arm, normally holding the arm slightly elevated, a rigid pivot on the free end of the

arm, on which said pantograph has bearings to swing in a plane parallel with the face of said plate when the pantograph is in its working position, by which arrangement substantial up and down movement of all parts of said pantograph is effected. 5

7. In a lettering machine, a support, a master copy mounted on said support, a pantograph for copying the characters of the master copy, having a drawing member, a tracer, and a spring connected with the pantograph and the tracer, normally holding the tracer at its lowest position on said pantograph, an arm having bearings on said support for angular movement in a vertical plane, the longitudinal limits of the bearings of said arm being sufficient distance apart to prevent lateral and twisting flexibility of said arm, a spring connected with said support and said arm normally holding the arm slightly elevated, a rigid pivot on the free end of said arm, on which said pantograph is mounted for angular movement in a horizontal plane, by which arrangement substantial up and down movement of all parts of said pantograph is effected, bringing the drawing member, in all of its positions of adjustment, into contact with the drawing surface promptly after the tracer contacts with the master copy. 15 20 25

8. In a lettering machine, a supporting plate having a circular opening, an annular member, having bearings around said circular opening, an annular plate mounted on said member, rotatable therewith, having master characters thereon, and a notch for each character, a pawl pivoted to said supporting plate, a spring for holding it in engagement with any one of said notches, and a pantograph mounted on said supporting plate to extend over said circular opening, for copying said characters through said opening on a drawing surface over which said supporting plate may be arranged to move. 30 35 40

9. A lettering machine, comprising, a support, an axle journaled on said support, a wheel fixed on each end of said axle, for parallel rolling movement of said lettering machine on a drawing surface, a master copy mounted on said support, a pantograph mounted on said support, for copying the characters of the master copy on a drawing surface, two bars attached to and extending from said support having a shoulder to abut against one edge of a straight-edge of the type having means for maintaining parallelism of its movement, and a block on each bar adjustable to the opposite edge of said straight-edge, slidably thereon, said straight-edge preventing angular displacement of said lettering machine. 45 50 55

10. A lettering machine, comprising a support, an axle journaled on said support, a wheel fixed on each end of said axle, for parallel rolling movement of said lettering machine on a drawing surface, a master copy mounted on said support, a pantograph mounted on said support, for copying the characters of the master copy on a drawing surface, a protractor of the type having parallel jointed rods connected to the protractor and to a drawing board, for maintaining parallelism of its movement, and means rigidly connecting said lettering machine with said protractor, detachable therefrom, for preventing angular displacement of the lettering machine. 60 65 70

11. In a lettering machine, a support, a plate having spaced master characters thereon, and means mounting said plate for movement horizontally on said support, a pantograph mounted 75

on said support, a shaft vertically mounted on said support, having spiral grooves, a nut having internal threads engaging said grooves, means for preventing rotation of said nut, a handle 5 connected with said nut whereby up and down movement of said nut will revolve said shaft, a driving member fixed to the lower end of said shaft having a driving connection with said plate for imparting movement thereto, locating means 10 on said plate, holding means on said support

adapted to cooperate with any one of said locating means when the locating means is moved into contact with the holding means by movement of said plate, whereby the plate is held stationary with the character corresponding to the locating means engaged, in position for being traced and copied by said pantograph in line on a drawing surface over which said support may be arranged to move.

LEONARD McDONALD. 10
